(57) **CLAIM**

The ornamental design for a support structure for debris collection bag, as shown and described.

DESCRIPTION

FIG. 1 is a right side, top front perspective view of an embodiment of the support structure for debris collection bag, illustrating the novel design.

FIG. 2 is the right side, top back perspective view thereof.

FIG. 3 is the front view thereof.

FIG. 4 is the back view thereof.

FIG. 5 is a right side view thereof, the left side being a mirror image of the right side.

FIG. 6 is the top view thereof.

FIG. 7 illustrates the bottom view thereof; and,

FIG. 8 is another right side, top front perspective view thereof.

The broken lines shown in the drawings are included for the purpose of illustrating environmental structure and form no part of the claimed design.
